UNITED STATES PATENT OFFICE.

HENRIETTA WILMER LAWRENCE, OF BALTIMORE, MARYLAND.

GAS-RANGE.

1,098,272.

Specification of Letters Patent. Patented May 26, 1914.

Application filed July 28, 1913. Serial No. 781,672.

To all whom it may concern:

Be it known that I, HENRIETTA WILMER LAWRENCE, a citizen of the United States, residing at Baltimore, in the State of Maryland, have invented certain new and useful 5 Improvements in Gas-Ranges, of which the following is a specification.

My present invention pertains to improvements in gas ranges the construction and advantages of which will be hereinafter set forth, reference being had to the annexed drawings, wherein:

Figure 1 is a vertical transverse sectional view, on the line 1—1 of Fig. 2; Fig. 2 15 a similar view on the line 2—2 of Fig. 1; Fig. 3 is a perspective view of the lower portion of the range, showing the adjustable baffle-plate and the mechanism for raising or lowering the same; and Fig. 4 a sectional plan of the lower portion or floor of the range.

The main object of the invention is to provide means whereby the lower portion of the range may be converted into an oven, 25 a broiling chamber or a boiling chamber, as may be desired.

A further object of the invention is to provide means for manipulating the adjustable baffle-plate employed to produce the 30 chambers aforesaid.

With these and other objects in view reference is made to the annexed drawings, wherein 1 indicates the main body of the range; 2 the upper oven, beneath the bottom 35 of which are arranged the gas-burners 3. Said burners, of course, may be of any type, and those shown are merely illustrative.

Preferably the walls of the oven will be spaced away from the main portion of the 40 range, thus forming ducts or passages 4, which open into a chamber 5 located below the burners 3. The lower end of said chamber is defined by a bottom plate 6, provided with slats or cross-bars 7, located centrally 45 thereof, and beneath which there is mounted a slide 8. A burner 9 is arranged beneath said slide, and when the slide is closed the heat and products of combustion emanating from the burner pass up through openings 10 50 (Fig. 4) formed in the bottom plate 6, and enter flues or spaces left between the outer walls of the range and the inner side walls 11 and 12 of the chamber 5. Said walls will be provided with oppositely-disposed shelf 55 or pan supports 13. Each of the walls 11 and 12 is provided with a pair of vertically-

disposed ways or channels 14, adapted to receive wires or cables 15, which pass over pulleys 16 suitably supported adjacent the upper ends of said channels, the wires or cables passing down into the space formed between the walls 11 and 12, and the outer wall of the range. They likewise pass through the openings 10 (see Fig. 3) and are connected to a winding shaft 17, mounted in suitable bearings in the lower portion of the range and extending transversely thereof, as best indicated in Fig. 1. The outer end of the shaft will be provided with a crank 18, which carries a spring-pressed locking pin 19, adapted to coact with openings 20 formed in a plate 21, fixedly secured to the wall of the range. The opposite ends of said cables are connected in pairs to the ends of cross-bars 22 and 23, 75 the ends of said bars passing into the channels or ways. A baffle-plate 24 is secured to said bars 22 and 23, and may be raised or lowered as desired by proper manipulation of the crank 18 upon the withdrawal of 80 the locking-pin 19. The baffle-plate will preferably be provided with a downwardly-extending flange 25 upon each end, and these flanges will be perforated or provided with openings, 26. Openings 27 will likewise be formed, preferably adjacent the ends of the baffle-plate, said openings and the openings 26 permitting the free passage of the heat from the lower portion of the chamber to the upper portion thereof.

It is to be understood that in so far as the generic invention is concerned any suitable mechanism may be employed for raising and lowering the baffle-plate to bring about the desired relationship of said baffle-plate 95 to the other portions of the range. If it be desired to convert the upper portion of the chamber 5 into a broiling oven, the plate will be positioned as shown in the drawings, at which time the slide 8 will preferably be 100 closed, and at the same time baking may be accomplished in the lower portion of the range, beneath the baffle-plate 24. A roast placed upon the baffle-plate will then be subjected to the heat of the flame of the burners 105 3 and likewise to the heat which emanates from the burner 9 and passes up around the lower chamber 5. At the same time several sauce-pans may be placed on the cross-bars 7, and the burner 9 utilized for the purpose 110 of boiling. If desired, the slide may be withdrawn and the heat from the burner 9

allowed to pass directly up beneath the baffle-plate 24.

If the upper portion of the chamber 5 is to be used merely as a broiler, the baffle-plate will be raised to the upper dotted line position, to bring it into proper relation to the burners 3. When so elevated, the lower portion of the chamber 5 will be relatively clear, and this will in effect convert the lower portion of the range into a relatively large second oven, defined by the under face of the baffle-plate and the bottom plate 6. If it be desired to use the chamber thus formed as a boiling chamber, the slide 15 8 will be withdrawn, and the vessel containing the article to be boiled placed upon the cross-bars 7, the products of combustion and any steam which may be generated, of course, passing up through the openings in the baffle-plate and around the edges of the same, thence through the upper portion of the chamber 5 into the ducts or passages 4 to the vent stack usually employed with gas-ovens at the present time.

25 When the baffle-plate is brought to its lowermost position, as shown by the lower dotted line in Fig. 1, the entire chamber 5 will be converted into one large roasting oven, the heat passing from the burner 9, 30 if the slide 8 be open, being deflected by the baffle-plate 24 and passing through the openings 26 and 27, thereby causing a proper circulation of heat upwardly through the chamber 5.

35 Having thus described my invention, what I claim is:

1. In a gas range, the combination of an upper oven; burners located beneath the same in close proximity thereto; a chamber beneath said burners having flues or passages arranged exteriorly thereof and extending from a point adjacent its bottom and discharging into the space below the upper oven; a burner located beneath the 45 bottom of said lower chamber; and a baffle-plate adjustably mounted in said chamber.

2. In a gas range, the combination of a body portion; an oven located in the upper portion thereof; burners located beneath the 50 oven in close proximity thereto; a chamber beneath said burners, the bottom of said chamber being spaced away from the bottom of the body; flues extending upwardly from the space between said bottoms; a burner 55 located in said space beneath an opening formed in the bottom of the chamber; means for closing said opening; and a baffle-plate adjustably mounted in said chamber.

3. In a gas range, the combination of an 60 oven; burners located immediately beneath

the same; a chamber beneath said burners; a burner located in the lower portion of the range below the floor of said chamber, said floor having an opening therein to permit the passage of products of combustion from 65 said burner upwardly through the same; a slide located over said burner and adapted to close said opening; a baffle-plate located in the chamber aforesaid; and means for raising or lowering said baffle-plate and 70 holding the same in its adjusted position.

4. In a gas range, the combination of an upper oven; burners located beneath the same; a chamber formed below said burners, the side walls whereof are provided with a 75 pair of vertically-disposed ways or channels; a baffle-plate located in said chamber; cross-bars secured to said baffle-plate and terminating at their ends in said vertically-disposed ways or channels; a pulley located 80 adjacent the upper end of each of said channels; a winding shaft located in the lower portion of the range; cables passing from the ends of the cross-bars upwardly through the channels, over the pulleys, and downwardly to the winding shaft; and means for rotating said shaft and locking the same in its adjusted position.

5. In a gas range, the combination of a body portion; an oven located in the upper 90 portion thereof; burners located beneath the oven in close proximity thereto; a chamber beneath said burners, the bottom of said chamber being spaced away from the bottom of the body; flues extending upwardly from 95 the space between said bottoms; a burner located in said space beneath an opening formed in the bottom of the chamber; means for closing said opening; and a baffle-plate mounted in said chamber and adjustable as 100 to height therein, said plate being provided with perforations whereby heated air may pass therethrough.

6. In a gas range, the combination of an upper oven; burners located beneath the same and in close proximity thereto; a chamber beneath said burners; a burner located in the lower portion of the range and below the chamber aforesaid; and a plate mounted in said chamber and adjustable as to height 110 therein, said plate being provided with perforations adjacent its marginal portions, whereby heated air may pass therethrough.

In testimony whereof I have signed my name to this specification in the presence of 115 two subscribing witnesses.
